(57) **CLAIM**

The ornamental design for a grooming equipment for animals, as shown and described.

DESCRIPTION

FIG. 1 is a front perspective view of a grooming equipment for animals, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1;

FIG. 10 is an enlarged detail view of area 10 in FIG. 1;

FIG. 11 is an enlarged detail view of area 11 in FIG. 2;

FIG. 12 is a perspective view thereof, shown in an environment of use;

FIG. 13 is a perspective view thereof, shown in an environment of use;

FIG. 14 is a perspective view thereof, shown in an environment of use;

FIG. 15 is a perspective view thereof, shown in an environment of use; and,

FIG. 16 is a perspective view thereof, shown in an environment of use.

The broken lines in the drawings illustrate the portions of the grooming equipment for animals, which form no part of the claimed design.

The dash-dot-dash broken lines encircling the enlarged views are for annotative purposes only and form no part of the claim thereof.

The dot-dash broken lines in the drawings are included to show a symbolic break in the length of the grooming equipment for animals. The appearance of any portion of the article between the break lines forms no part of the claimed design.

1 Claim, 16 Drawing Sheets
